DOOR CLOSER

William Stanley Richmond, Hamilton, Ontario,
Canada

Application May 21, 1937, Serial No. 143,968

7 Claims. (Cl. 16—59)

This invention relates to improvements in door closers of the type wherein oil or another viscous liquid is employed as the rebound retarding agent, and consists essentially of a relief passage in the 5 diaphragm and an automatically opened valve or closure therefor.

The crankshaft of most door closers is journaled in a bushing which is usually formed in two parts with packing between them and which is 10 especially fitted within a hub-like bearing formed as one with the diaphragm. The packing is intended to exclude the liquid from the spring case where otherwise it would be forced or "pumped" by the action of the piston, particularly on the 15 rebound retarding or checking stroke. However, the packing soon loses its temper and then fails as an absolute resistant, and a certain amount of liquid gets past the packing along the crankshaft and into the spring case, where it remains owing to its inability to return the way it came. The 20 liquid having thus accumulated in the spring case is inert and soon becomes gummy or sticky and produces a consequent ill-effect upon the efficiency of the mechanism residing in that case. Moreover, the normal quantity of fluid with which 25 the crank case and cylinder are charged is continually lessened in this process resulting in the necessity of a frequency of recharging and over-hauling.

While the decomposition of the liquid pumped 30 into the spring case as previously set forth adversely affects the efficiency of the device there is no harm done if the fluid is pumped into the spring case so long as it returns to its source.

Obviously the multiplication of the pumped 35 liquid could be obviated by the simple remedy residing in a perforate diaphragm wherethrough the fluid pumped into the spring case could seep back into the cylinder while the device is at rest, 40 but since the apparatus may be caused to repeatedly assume any number of different positions and perhaps permitted to remain in an inverted position over undetermined periods during its peregrination, there might conceivably be more 45 oil in the spring case than in the cylinder. Consequently, holes in the diaphragm, unless they were closed during the period between the production and mounting of the device, would defeat their purpose.

50 Therefore, the principal object of the present invention is to provide means for temporarily closing a communication opening in the diaphragm of a door closer of the kind described until it is mounted, and for automatically and

permanently removing the closure from the opening on the initial operation of the device.

A second important object is to lessen the cost 5 of these door closers by means of the elimination of the usual crankshaft bushings and packing, or at least to offset the cost of the said invention by means of such elimination.

With the above and other objects in view as will be hereinafter apparent, the invention consists in general of certain novel details of construction and combinations of parts hereinafter 10 fully described, illustrated in the accompanying drawing and specifically claimed.

In the accompanying drawing like characters of reference indicate like parts in the several 15 views, and:

Figure 1 is a side elevation of a door closer constructed in accordance with this invention, and shown partially in vertical median cross-section.

Figure 2 is a top cross-sectional view taken on 20 the lines 2—2 of Figure 1, with the spring removed and showing the closure or valve in closed position.

Figure 3 is a similar view showing the valve in open position.

Figure 4 is a side elevation of the spring driver.

Figure 5 is a bottom view of the spring driver.

Figure 6 is a side view of the closure or valve.

On the drawing a door closer is shown with the 30 important conventional parts identified as follows: The cylinder is indicated by the numeral 10, the piston by 11, 12 indicates the fluid duct, 13 the crank, 14 the crank shaft, 15 the crank case, 16 the spring case, 17 the spring, 18 the spring pusher, 19 the ratchet, and 20 the main arm. The general construction and operation of 35 the foregoing parts are well-known and hence need not be described.

The diaphragm 21 of the present invention has a flat upper surface and is provided with a plurality of radial tongues 22 which fit into conforming internal perpendicular channels in the spring case 16, and is removably mounted on an annular supporting gallery 23. These channels permit the tongued diaphragm to be inserted from the 40 top of the spring case and assure the registry of the screw holes in the diaphragm and in the 45 said gallery for convenience in the application of the retaining screws 24. The crank shaft 14 is journaled in a bearing 25 slung from this diaphragm.

In its present embodiment the invention consists of a pair of holes 26 in the diaphragm and a pair of valves or closures 27 pivoted (28) to the 50 diaphragm close to its periphery.

During the assembly of the door closer and before the cylinder and crank case are charged with the retarding agent or fluid the holes 26 are closed by the valves 27 which engage edgewise a cam 29 formed on the lower end of the spring pusher 18.

These valves are preferably in the form of slightly arcuate spring leaves having nodules 30 adapted to snap into the holes 26 in order to assure an absolute seal.

In practice the conventional ratchet engaging dog or pawl (not shown) is not engaged with the ratchet until the device has been mounted on a door and is ready for service adjustment, where-
15 after the device is obviously immune to non-up-
right position. Consequently the revoluble pos-
ition of the spring pusher and cam remains un-
altered from the time of assembly until the pawl
is engaged and the door with the device attached
20 is opened for the first time on test.

When the spring pusher is revolvably moved for the first time after the valves are set in closed position during assembly the cam 29 moves or spreads the valves to open position, as can be clearly seen in Figure 3, where they remain so long as the door closer continues in service, and thus the fluid theretofore confined in the cylinder and crank case is henceforth free to circulate between the latter and the spring case.

30 Since it requires little short of the act of opening the door upon which the closer is mounted for sufficient purchase to revolvably move the spring pusher against the resistance of the spring there is obviously little danger of the valves ac-
35 cidentally opening during the period in which they are intended to remain tightly closed as afore-
said.

There has thus been provided a simple and efficient device of the kind described and for the purpose specified.

It is obvious that minor changes may be made in the form and construction of the invention without departing from the material spirit thereof. It is not, therefore, desired to confine the invention to the exact form herein shown and de-
45 scribed, but it is desired to include all such as properly come within the scope claimed.

I claim:

1. In a door closer of the class described in-
cluding a diaphragm provided with an opening,
a valve adapted to temporarily close the opening,
and means for operating the valve to per-
manently clear the opening automatically upon
the initial operation of the door closer. 5

2. In a door closer of the class described in-
cluding a diaphragm provided with an opening,
a valve adapted to temporarily close the opening,
and means for operating the valve to per-
manently clear the opening automatically upon
the initial operation of the door closer, said means
consisting of a cam controlled by a revoluble
member of the door closer. 15

3. In a door closer of the class described in-
cluding a diaphragm provided with an opening,
a valve adapted to temporarily close the opening,
and means for operating the valve to per-
manently clear the opening automatically upon the initial
20 operation of the door closer, said valve being set
to temporarily close the opening during the as-
sembly of the door closer.

4. In a door closer of the class described in-
cluding a spring pusher and a diaphragm provid-
ed with an opening, a valve adapted to tem-
porarily close the opening, a cam associated with
the spring pusher and adapted to operate the
valve to permanently clear the opening auto-
matically upon the initial operation of the spring
pusher. 25

5. In a door closer of the class described in-
cluding a spring pusher and a diaphragm pro-
vided with an opening, a closure in temporary
registry with the opening, a cam associated with
the spring pusher and adapted to permanently
shift the closure from said registry automatical-
ly upon the initial operation of the spring pusher. 35

6. The device according to claim 1 and in
which the valve consists of a slightly arcuate
spring leaf pivoted to the diaphragm and pro-
vided with a nodule for engaging the opening.

7. The device according to claim 5 and in
which the cam is formed as one with the spring
pusher.

WILLIAM STANLEY RICHMOND.
